JOHN F. TOOMEY, OF NEW YORK, N. Y., ASSIGNOR TO AMERICAN TELEPHONE AND TELEGRAPH COMPANY, A CORPORATION OF NEW YORK.

BUSY BACK CIRCUITS.

1,381,368.

Specification of Letters Patent. Patented June 14, 1921.

Application filed April 1, 1919. Serial No. 286,660.

To all whom it may concern:

Be it known that I, JOHN F. TOOMEY, residing at New York, in the county of New York and State of New York, have invented 5 certain Improvements in Busy Back Circuits, of which the following is a specification.

This invention relates to telephone systems and more particularly to means for 10 indicating when a called line is busy.

The invention consists in the provision of improved means whereby the busy condition 15 of a called subscriber's line may be indicated in the case of a local call to the operator at the office wherein the call originated or in the case of a long distance call to the operator at the incoming long distance or toll switchboard. It further consists in the provision of improved means for transmitting 20 an audible as well as visual busy signal to such an operator for the purpose of making the signal more easily distinguishable. Other and further features of the invention will be clear from the detailed description to 25 be given later.

A telephone call between subscribers' lines associated with different central offices or exchanges, is completed by means of trunk 30 circuits interconnecting such offices. The operator at the office wherein the call originates communicates with the operator at the exchange of the called subscriber and then connects her cord circuit with a suitable trunk circuit designated by the latter operator, which trunk circuit is then connected 35 with the line of the called subscriber. In the case of a long distance or toll call, the connection is completed in a similar manner over toll switching trunks. Should the line 40 of the called subscriber be found to be busy or in use there is provided at the switchboard of the central office associated with the called subscriber's line a set of busy jacks into which the local trunk circuit may 45 be inserted and an additional set of busy jacks into which the toll switching trunk may be inserted in the case of a toll call. These busy jacks are associated with busy 50 back circuits which include apparatus for intermittently closing circuits associated with the trunk circuits and the cord circuits of the calling operator whereby the supervisory signals associated with the calling operator's cord circuit will be caused to flash and inform the operator of the busy condition of 55

the called line. In former arrangements of this character two separate sets of busy jacks were provided, one set suitable for use with local trunk circuits and the other set suitable for use with toll switching 60 trunks. Such arrangements have been found to be unreliable should a local trunk be inserted in one of the jacks adapted for a toll switching trunk or should a toll switching trunk be inserted in one of the 65 jacks suitable for a local trunk. Furthermore if a defective local trunk or defective toll trunk is connected with former types of busy back circuits, the busy back signals applied to other lines connected to the busy 70 back circuit would fail until the defective trunks are removed. Also in offices having machine ringing trunks, a considerable amount of interference is noted when a machine ringing trunk is plugged into the busy 75 back circuit. In order to eliminate such interference and to do away with the above mentioned difficulties, the busy back circuit embodied in this invention has been provided.

In the busy back circuit of this invention but one set of jacks is provided adapted to be used with either local trunk circuits or toll switching trunks. When a trunk is associated with one of the jacks, relay means 80 connected to the sleeve circuits of all the jacks will operate and close a circuit including additional relay means and an interrupting apparatus thereby causing these other relay means to function intermittently. 85 The operation of these relay means serves to complete individual busy signaling circuits for each one of the jacks. Additional means are provided for superimposing an audible signal on the busy back circuit as 90 will appear more fully in the detailed description of the operation.

In the drawing, Figures 1 and 2 when taken together illustrate a circuit diagram of a preferred form of the arrangements of 100 the invention. In Figs. 3 and 4 are illustrated modifications thereof.

In Fig. 1 are illustrated types of cord circuits and trunk circuits suitable for completing local and long distance calls. These 105 types of cord circuits and trunk circuits are well known in the art and only portions thereof essential for the operation of this invention are illustrated. A local cord circuit 1 is shown terminating into plugs P_1 110

and P_2 . Associated with ring conductor of cord circuit 1 is the supervisory relay 5 adapted to control the supervisory lamp 6. The local cord circuit 1 may be associated with the local trunk circuit 2 by means of the jack J_2 . Included in the trunk circuit 2 is the repeating coil 9. Associated with one of the windings thereof is the relay 7 having two windings, one of high and one of low resistance. Associated with the talking conductors of trunk 2 is the supervisory relay 8 which serves to close a short circuit about the high resistance winding of relay 7 and thus controls the operation of relay 5. The relay 7 controls the usual type of guard or disconnect signal such as the lamp 11 associated with the sleeve relay 10 of the plug P_3 . For completing a long distance call, the toll cord circuit 3 is employed. Included in a bridge across the talking conductors of toll cord 3 are the high impedance windings 13 and the supervisory relay 14 which controls the signal lamp 15. A toll switching trunk 4 is shown including the repeating coil 16 associated with one of the windings of which is the relay 18 and a source or current 19 which serves to operate relays 14 and 18. Associated with the other winding of repeating coil 16 is the supervisory relay 20 and the relay 17 which, in turn, controls the relay 14.

In Fig. 2 is shown a preferred form of the busy back circuit embodied in this invention. Associated with the sleeve conductors of the jacks J_{12} , J_{13} , J_{14} , J_{15} , J_{16} and J_{17} is the relay 53 which operates whenever a trunk is associated with one of said jacks. Included in the sleeve and ring conductors associated with the jacks are resistance elements adapted to simulate a subscriber's line. The operation of relay 53 serves to complete circuits for relays 56 and 57 which circuits include the interrupting apparatus 54. The relays 56 and 57 serve to complete individual busy signal circuits for each of the jacks as will be pointed out more fully in the description of the operation.

In Figs. 3 and 4 are illustrated modifications of the arrangement shown in Fig. 2. In Fig. 3 a transformer 32 is illustrated with which is associated an interrupter 33 and a source of current. The transformer 32 is associated in common with the ring conductors of all of the jacks of the busy back circuit and provides a means for transmitting an audible busy signal over lines connected therewith. In the Fig. 4 an audible busy signal is impressed on the busy back circuit by means of the transformer 44 associated with a conductor connected to the tip contacts of all the jacks. Associated with transformer 44 are the interrupters 45 and 79 which are adapted to function at different speeds.

65 The invention may now be more fully un-

derstood from the following description of its operation. In the case of a local call, if the operator finds that the subscriber desires a connection with a line associated with another central office, she communicates with the operator at such office by means of a call wire circuit and is informed by the latter operator of a suitable trunk circuit, such as the trunk circuit 2, with which to associate her cord circuit, such as the cord circuit 1. 70 When the cord circuit 1 is connected with trunk 2 by means of the plug P_2 being inserted in jack J_2 , the following circuit is completed; from ground, sleeve conductor of jack J_2 , sleeve contacts of jack J_2 and plug P_2 , sleeve conductor of plug P_2 , resistance 62, conductor 64, filament of lamp 6, to battery. The closing of this circuit will operate lamp 6. The insertion of plug P_3 into jack J_2 also closes the following circuit: 80 from one side of battery 65, tip conductor of cord 1, tip contacts of plug P_2 and jack J_2 , tip conductor of trunk 2, upper left hand winding of coil 9, conductor 66, high and low resistance windings of relay 7, conductor 67, lower left hand winding of coil 9, ring conductor of trunk 2, ring contacts of jack J_2 and plug P_2 , ring conductor of cord 1, winding of relay 5, ring conductor of cord 1, to the opposite side of battery 65. 90 The upper winding of relay 7, however, is of sufficiently high resistance so that the closing of this circuit will not operate supervisory relay 5. The local call is completed by the operator at the central office, with which the 100 called subscriber's line is associated, inserting the plug P_3 of the trunk 2 into the jack of the called subscriber's line. Upon the operation of relay 7, a circuit is completed from ground and battery, filament of lamp 11, contact and armature of relay 7, armature and back contact of relay 10, lower winding of relay 10 to ground. The closing of this circuit will light lamp 11 but will not operate relay 10 at this time as the lower 110 winding of relay 10 is marginal and will prevent the operation of the relay at this time. When the plug P_3 is inserted in the jack of the called line or the busy back jack, a circuit is completed from ground in the 115 sleeve circuit of the jack sleeve, circuit of the plug P_3 , upper winding of relay 10 to battery and ground. The closing of this circuit will operate relay 10 and the circuit for lamp 11 will now be completed as follows: 120 from ground to battery, filament of lamp 11, contact and armature of relay 7, armature and front contact of relay 10 through a low resistance to battery and ground. The circuit for the lamp 11 will be completed as described instead of through the upper winding of relay 10, because the resistance in said circuit is lower than that of the resistance of the upper winding of relay 10 and acts as a shunt therefor. As battery is found at 130

- both ends of this circuit, the lamp 11 will be extinguished at this point. When the called subscriber responds, the following circuit is closed: from ground, upper right hand winding of coil 9, tip conductor of trunk 2, tip contact of plug P_2 , out over the subscriber's line, through the subscriber's substation, back over the subscriber's line, ring contact of plug P_2 , ring conductor of trunk 2, winding of relay 8, ring conductor of trunk 2, lower right hand winding of coil 9, to battery 70. The closing of this circuit will energize relay 8 which will pull up its armature and close a short circuit including conductors 68 and 69 about the high resistance winding of relay 7, so that the circuit formerly closed through relay 5 will no longer include the high resistance winding of relay 7, and relay 5 will now operate.
- 20 The operation of relay 5 closes a circuit from battery, filament of lamp 6, conductor 64, resistance 63, armature and contact of relay 5, to battery. As resistance 63 is of smaller value than resistance 62, the closing 25 of this circuit will provide battery at both ends of the circuit for lamp 6 and accordingly extinguish signal lamp 6 and thus inform the operator that the connection has been completed.
- 30 Should the line of the called subscriber be busy, the operator at the central office with which the subscriber is associated will insert the plug P_3 of trunk 2 into one of the jacks of the busy back apparatus 51, such for example as the jack J_{12} , thereby closing the following circuit: from battery, filament of disconnect signal lamp 11, winding of relay 10, sleeve conductor of plug P_3 , sleeve contacts of plug P_3 and jack J_{12} , sleeve conductor of jack J_{12} , conductor 52, winding of relay 53, to ground. This will operate relay 53 and close the following circuit: from battery, winding of relay 56, conductors 59 and 60, contact and armature of relay 53, conductor 55, interrupter 54, to ground. This will energize relay 56 and close the following circuit: from ground, conductor 61, conductor 71, contact and armature of relay 56, conductor 72, ring contacts of jack J_{12} and plug P_3 , ring conductor of trunk 2, winding of relay 8, ring conductor of trunk 2, lower right hand winding of coil 9, to battery 70. The closing of this circuit will operate relay 8 which in a manner previously pointed out 55 will short circuit the high resistance winding of relay 7 and cause the operation of supervisory relay 5 in cord circuit 1, which in turn and as previously pointed out will extinguish the signal lamp 6. However as the previously traced circuit including the winding of relay 56 includes the interrupter 54, the relay 56 will function intermittently. Accordingly, the relays 8 and 5 will be caused to operate intermittently and the signal lamp 6 will be caused to flash intermittently, thereby informing the operator that the called line is busy. Upon being thus informed of the busy condition of the called line the operator removes the plug P_2 from the jack J_2 , thereby opening the previously described circuit through relay 7 and de-energizing relay 7. The deenergization of relay 7 serves to open the usual circuit controlled thereby and to cause the functioning of the usual disconnect signal 11, whereupon the trunk 2 may be disassociated from the busy jack. As the operation would be substantially the same as described were a connection to be made with any of the other jacks of the busy back circuit 51, such as jacks J_{13} , J_{14} , J_{15} , J_{16} , or J_{17} , no further description thereof will be given.
- The operation, when a trunk circuit such as the trunk 2 is associated with a busy back circuit such as the circuit 49 illustrated in Fig. 3, is as follows: The plug P_3 is inserted in one of the jacks such as the jack J_{19} , and the following circuit is closed: from battery, filament of lamp 11, winding of relay 10, sleeve conductor of plug P_3 and jack J_{19} , conductors 46 and 47, winding of relay 48 to ground. This operates relay 48, thereby closing the following circuit: from battery, winding of relay 26, conductor 25, contact and armature of relay 48, conductor 24, interrupting apparatus 23, to ground. The closing of this circuit will energize relay 26, thereby closing the following circuit: from ground, winding of transformer 32, conductors 29, 30 and 73, armature and contact of relay 26, conductor 74, ring contacts of jack J_{19} and plug P_3 , ring conductor of trunk 2, winding of relay 8, ring conductor of trunk 2, lower right hand winding of coil 9, to battery 70. The closing of this circuit will operate the relay 8 which in a manner as previously pointed out will operate the relay 5 and the supervisory signal lamp 6. As the circuit, including the winding of relay 26, includes the interrupter 23, the relay 26 will function intermittently. Accordingly the relays 8 and 5 will function intermittently and the supervisory signal lamp 6 will be caused to flash in a manner as previously pointed out, thereby informing the operator of the busy condition of the called line. An audible signal will at the same time be transmitted to the subscriber and to the operator's telephone set associated with cord circuit 1, as follows: The functioning of interrupter 33, together with transformer 32, will cause a current of audible frequency to be transmitted as follows: from transformer 33, over conductors 29, 30 and 73, armature and contact of relay 26, conductor 74, ring contacts of jack J_{19} and plug P_3 , ring conductor of trunk 2, right hand windings of transformer 9, tip conductor of trunk 2, tip contacts of plug P_2 and jack J_{19} , over conductor 75, to ground. This current of audible frequency

will then be transmitted through transformer 9, over the talking conductors of trunk 2 and cord circuit 1 in the usual manner. As the operation would be substantially the same if the trunk circuit 2 were associated with any of the other jacks of busy back circuit 49, no further description thereof will be given.

If a trunk circuit such as the circuit 2 should be associated with the form of busy back circuit, as illustrated in Fig. 4, the operation would be as follows: The plug P_3 would be inserted in one of the jacks of circuit 50, such as the jack J_{11} , and the following circuit would be closed: from battery, filament of lamp 11, winding of relay 10, sleeve conductor of plug P_3 , sleeve contacts of plug P_3 and jack J_{11} , sleeve conductor of jack J_{11} , conductors 34 and 35, winding of relay 36, to ground. This will operate relay 36 and close the following circuit: from battery, winding of relay 39, conductor 38, contact and armature of relay 36, conductor 42, interrupting apparatus 37, to ground. The closing of this circuit will operate relay 39, thereby closing the following circuit: from ground, conductors 76 and 77, armature and contact of relay 39, conductor 78, ring contacts of jack J_{11} and plug P_3 , ring conductor of trunk 2, winding of relay 8, ring conductor of trunk 2, lower right hand winding of coil 9, to battery 70. The closing of this circuit will operate the relay 8 which in the same manner as previously pointed out will operate the relay 5 and the supervisory signal 6. As the circuit controlling relay 39 includes the interrupting apparatus 37, the relay 39 will operate intermittently. Accordingly, the relays 8 and 5 will operate intermittently and the supervisory signal 6 will be caused to flash, thereby informing the operator of the busy condition of the called line. At the same time an audible signal will be transmitted to the subscriber and to the operator's telephone set associated with cord circuit 1 in the following manner: Associated with the conductor 43, connected in common to the tip contacts of all of the jacks of circuit 50, is the transformer 44. Associated with one winding of transformer 44 is the interrupter 79 and a source of current. Associated with the other winding of transformer 44 is the interrupter 45 and a source of current. The interrupters 45 and 79 are arranged to function at different speeds. With such an arrangement of interrupters and the source of current together with the inclusion of a condenser in the circuit, a certain distinctive tone, which is easily distinguishable from other tones and of a desirable quality for the purpose for which it is intended, will be produced and may be transmitted over the trunk lines and circuits connected thereto. By this arrangement a current of audible frequency will be transmitted from transformer 44 as

follows: over conductor 43, tip contacts of jack J_{11} and plug P_3 , tip conductor of trunk 2, right hand winding of transformer 9, to ground. This current of audible frequency will then be transmitted by means of transformer 9 over the talking conductors of the trunk 2 and the cord circuit 1 in the usual manner.

In the case of a long distance or toll call, the plug P_4 of the toll cord circuit 3 is associated with the incoming long distance line. If the operator finds that a connection is desired with a line associated with another central office, she communicates with the operator at such office by means of a call wire circuit and is informed by the latter operator of a suitable toll switching trunk circuit, such as the toll switching trunk 4, with which to associate the toll cord 3. When the toll cord 3 is associated with the toll switching trunk 4 by means of the plug P_5 being inserted in the jack J_5 , the following circuit is closed: from ground, upper winding of relay 18, conductors 80 and 81, upper left hand winding of transformer 16, tip conductor of trunk 4, tip contacts of jack J_5 and plug P_5 , tip conductor of cord 3, conductor 82, high impedance winding 13, winding of relay 14, high impedance winding 13, conductor 83, ring conductor of cord 1, ring contacts of plug P_5 and jack J_5 , ring conductor of trunk 4, conductors 84 and 85, lower winding of relay 18, to battery 19 and ground. The closing of this circuit will energize relay 18. The energization of relay 18 will cause the following circuit to be closed: from ground and battery, filament of lamp 22, armature and contact of relay 21, lower winding of relay 17, conductor 88, contact and armature of relay 18, to ground. The closing of this circuit will operate relay 17. This will hold open at contact points 89 and 90 the previously traced circuit, including the windings of relay 14, and thus prevent relay 14 and lamp 15 from operating at this time. The relay 18, however, will remain energized over the following circuit: from ground, armature and contact of relay 17, conductor 85, lower winding of relay 18, battery 19 to ground. The operator at the central office with which the called subscriber's line is associated will now insert the plug P_6 of the toll switching trunk 4 into the jack of the called subscriber's line, thereby completing the connection. However, if the called subscriber's line is busy, the operator will insert the plug P_6 in one of the jacks of the busy back circuit 51, illustrated in Fig. 2, such, for example, as the jack J_{12} . When the plug P_6 is inserted in the jack J_{12} , the following circuit is closed: from ground and battery, winding of relay 21, sleeve conductor of plug P_6 , sleeve contacts of plug P_6 and jack J_{12} , sleeve conductor of jack J_{12} , conductor 52,

winding of relay 53, to ground. The closing of this circuit will operate relays 21 and 53. The operation of relay 21 will hold open at its armature and break contact the previously traced circuit through the lower winding of relay 17, thereby deenergizing relay 17. The deenergization of relay 17 will allow the formerly traced circuit through relay 14 to be completed, and will thus cause the lamp 15 to light, thereby informing the operator that a connection has been made by the trunk. The operation of relay 53 closes the following circuit: from ground and battery, winding of relay 56, conductors 59 and 60, contact and armature of relay 53, conductor 55, interrupter 54, to ground. The closing of this circuit energizes relay 56, thereby closing the following circuit: from ground, conductor 61, conductor 71, contact and armature of relay 56, conductor 72, ring contacts of jack J_{12} and plug P_6 , ring conductor of trunk 4, right hand lower winding of transformer 16, winding of relay 20 to battery and ground. The closing of this circuit will operate relay 20, thereby closing the following circuit: from ground and battery, conductor 95, upper winding of relay 17, conductor 86, contact and armature of relay 20, conductor 87, lower winding of relay 17, conductor 88, contact and armature of relay 18, to ground. The closing of this circuit energizes relay 17 which pulls up its armatures and opens at contact points 89 and 90 the circuit previously traced from battery 19, through the winding of relay 14, thereby deenergizing relay 14, which deenergization in turn causes the extinguishment of the signal lamp 15. The operation of relay 17 also closes the following locking circuit for relay 18: from ground and battery, lower winding of relay 18, conductor 85, contact and armature of relay 17, to ground. As the previously traced circuit about the winding of relay 56 includes the interrupting apparatus 54, the relay 56 will be caused to function intermittently. Accordingly the previously traced circuit closed upon the energization of relay 56 about the relay 20 will be continuously opened and closed, thereby causing relay 20 to operate intermittently. This in turn will cause the relay 17 to act intermittently, thereby continuously opening and closing the previously traced circuit from battery 19, through the winding of relay 14. This will cause the relay 14 to act intermittently, thereby causing the supervisory signal lamp 15 to flash continuously, thus informing the operator of the busy condition of the called line. As the operation would be substantially as described if the trunk 4 were connected with any of the other jacks of the busy back circuit 51, a further description of the operation thereof will be omitted. The toll switching trunk 4 may also be used with

the other forms of busy back circuits, such as illustrated in Figs. 3 and 4. As the details of the operation of the arrangements shown in Figs. 3 and 4 have already been described with respect to the local trunk circuit 2, and as their operation would be substantially similar to that already described when used with the toll switching trunk 4, a further description of the operation thereof will be omitted.

While the invention has been disclosed as embodied in certain specific arrangements which have been deemed desirable, it is understood that it is capable of embodiment in many and widely varied forms without departing from the spirit of the invention as defined in the appended claims.

What is claimed is:

1. In a telephone system, a cord circuit including a supervisory signal, a trunk circuit, means in said trunk for controlling said supervisory signal, a busy back circuit including a plurality of switching terminals, means to associate said trunk with one of said terminals, circuits individual to each of said switching terminals and adapted to control said means in said trunk, and means individual to each of said circuits for intermittently opening and closing said circuits.

2. In a telephone system, cord circuits adapted for local calls, cord circuits adapted for long distance calls, supervisory signals in said cord circuits, trunk circuits adapted for use with said local cord circuits, trunk circuits adapted for use with said long distance cord circuits, means in said trunk circuits for controlling said supervisory signals, a busy back circuit including a plurality of switching terminals, means to associate said trunks with said terminals, circuits individual to each of said switching terminals and adapted to control said means in said trunks, and means individual to each of said circuits for intermittently opening and closing said circuits.

3. A trunk circuit including a source of current and responsive means associated with the ring conductor thereof, a circuit including a plurality of switching terminals, means to associate said trunk with one of said terminals, means individual to each of said terminals for applying ground to the conductors associated with the ring contacts of said terminals, and means for intermittently operating said last mentioned means.

4. A busy back circuit including a plurality of jacks, conductors associated with the ring contacts of said jacks, means responsive upon the association of a trunk circuit with one of said jacks for applying ground to all of said ring conductors, and means individual to said ring conductors for disconnecting said ground.

5. A trunk circuit including responsive means, a busy back circuit including a plu-

5 rality of switching terminals, means to associate said trunk with any of said terminals, individual means associated with each of said terminals and responding when said 10 trunk is associated therewith for operating said responsive means, and means for intermittently operating said individual means.

10 6. A trunk circuit including responsive means, a busy back circuit including a plurality of jacks, means to associate said trunk with any of said jacks, a relay associated with the sleeve conductors of all of said jacks and responding whenever said trunk is 15 associated with one of said jacks, means controlled by said relay and individual to each of said jacks for operating said responsive means.

15 7. A trunk circuit including responsive means, a busy back circuit including a plurality of switching terminals, means to associate said trunk with any of said terminals, individual means associated with each of

said terminals and responding when said trunk is associated therewith for operating said responsive means, means for intermittently operating said individual means, and means for impressing a current of audible frequency on said individual means. 25

8. A trunk circuit including responsive means, a busy back circuit including a plurality of switching terminals, means to associate said trunk with one of said terminals, circuits individual to each of said switching terminals and adapted to control said responsive means, means individual to each of 35 said circuits for intermittently opening and closing said circuits, a source of current of audible frequency, and means to impress current from said source on said individual circuits. 40

In testimony whereof I have signed my name to this specification this 31st day of March, 1919.

JOHN F. TOOMEY.
